UNITED STATES PATENT OFFICE.

GEORGE L. TULLY, OF SOUTHBRIDGE, MASSACHUSETTS, ASSIGNOR TO AMERICAN OPTICAL COMPANY, OF SOUTHERIDGE, MASSACHUSETTS, A VOLUNTARY ASSOCIATION OF MASSACHUSETTS.

EYE-PROTECTOR.

1,248,758.

Specification of Letters Patent.

Patented Dec. 4, 1917.

Application filed July 30, 1917. Serial No. 183,536.

To all whom it may concern:

Be it known that I, GEORGE L. TULLY, a citizen of the United States, residing at Southbridge, in the county of Worcester 5 and State of Massachusetts, have invented certain new and useful Improvements in Eye-Protectors, of which the following is a specification.

This invention relates to improvements in 10 eye protectors and has particular reference to that type of goggle provided with side screen or shield for protecting the eyes of the wearer.

The leading object of the present invention 15 is the provision of an improved construction of side screen or shield member which shall have a portion formed from solid material to absolutely prevent access of undue lateral light or the like to the eye 20 of the wearer, and shall be additionally provided with a screen or protected apertured portion which will permit of free ventilation 25 of the space inclosed by the protector lens and shield and will at the same time have a general protective action.

A further object of my invention is the provision of an improved manner of constructing a shield of this character which shall at once be simple and inexpensive of 30 manufacture and at the same time produce a desirable construction.

Other objects and advantages of my improved construction should be readily apparent by reference to the following specification taken in connection with the accompanying drawings, and it will be understood that I may make any modifications in the specific details of construction shown and described within the scope of the appended 35 40 claims without departing from or exceeding the spirit of my invention.

Figure I represents a front view of a protector embodying my improvement.

Fig. II represents an end view thereof.

Fig. III represents a sectional view taken 45 as on the line III—III of Fig. II.

Fig. IV represents a plan view of the metallic stamping or blank.

Fig. V represents a plan view of a slightly 50 modified form of my invention.

Fig. VI represents a sectional view taken on the line VI—VI of Fig. I.

In the drawings, the numeral 1 denotes the bridge member of my improved pro-

tector having at each end a lens receiving 55 rim or frame 2 for the protecting lens 3 and having pivoted to said rim or frame 2 one of my improved shield members. Temples or like head engaging devices 4 serve to retain the mounting in position on the face of 60 the wearer.

By reference particularly to Figs. II and III it should be seen that my improved protector shield comprises a solid or non-perforated portion 5 and an apertured or 65 perforated portion 6, being illustrated in Fig. V as formed with the perforations 7 to permit of ventilation of the shield, and in Fig. II this portion being shown as having a plain aperture backed by a mesh or 70 screen 8.

In connection with Figs. III and IV it is to be noted that when the mesh 8 is employed the screen section comprises the main blank or non-perforated portion 5 and the 75 frame portion 8' inclosing the aperture 6. In addition the portions 5 and 8' are provided with the rim portions 10 adapted to be reversely bent and clamped against the screen 8 to securely lock the screen in position. This action of the rim 10 is supplemented by the rim portion 11 on the straight side of the screen which is also adapted to be reversely inwardly bent onto the back 80 side of the screen, thus providing a complete finished edge for the shield member 85 and at the same time securely locking the screening in position. Attention is further invited to the fact that the member 11 is provided with the ears 12 adapted to overlie the ears 13 on the screen proper, the said 90 parts having aligned perforations 14 to receive the pivots for the shield member.

In the form of construction specifically 95 illustrated in Fig. V the general construction is the same, in that the rim portions 10 and 11 are similarly provided to be reversely bent and form the neat finished edge for the shield, the only difference in this instance being that in place of employing the 100 mesh screen member 8 a plurality of perforations 7 are formed in the material itself, thus providing the necessary ventilation.

From the foregoing description the construction of my improved shield member 105 should be readily apparent and it will be seen that I have provided a novel form of shield, in that it is a solid or non-perforated

portion which may be disposed either at the top or at the bottom, as desired, and which will be an absolute protection against flying particles of metal, chips or the like 5 when the protector is worn in the industries, and will thus to the greatest degree prevent possible injury to the eye, while at the same time I have provided the apertured portion of the screen disposed at a point not exposed to the flying chips or other particles and which will provide satisfactory ventilation in the screen, preventing undue heating or discomfort to the face of the wearer.

I claim:

- 15 1. A shield for an eye protector, comprising a substantially triangular body portion having one half thereof perforated for ventilation purposes, said body portion having a plurality of members projecting therefrom, including a pair of ears at two sides thereof, and a rim strip connecting one of the ears of each pair, whereby when the rim is reversely folded onto the shield the ears connected thereby will overlie the other ears of the pair and in connection therewith form a durable pivot joint for the shield, substantially as illustrated.
- 20 2. An eye protector including a pair of lens receiving frames, means for securing the frames in position on the face of the wearer, shield members pivoted to the frames and of substantially triangular form extending from the frames to the face of the

wearer adjacent the temples and said triangular shield members each comprising a 35 solid protective portion and a perforated ventilating portion disposed upon opposite sides of the center line of the triangular shield member.

3. An eye protector including a pair of 40 lens receiving frames, means for securing the frames in position on the face of the wearer, shield members pivoted to the frames and of substantially triangular form 45 extending from the frames to the face of the wearer adjacent the temples and said triangular shield members each comprising a solid protective portion and a perforated 50 ventilating portion disposed upon opposite sides of the center line of the triangular shield member, each shield member having a plurality of members projecting therefrom, including a pair of ears at two sides thereof, and a rim strip connecting one of the ears of each pair, whereby when the rim 55 is reversely folded onto the shield the ears connected thereby will overlie the other ears of the pair and in connection therewith form a durable pivot joint for the shield.

In testimony whereof I have affixed my 60 signature, in presence of two witnesses.

GEORGE L. TULLY.
